UNITED STATES PATENT OFFICE.

RUDOLPH SIEBERT, OF ROCHESTER, NEW YORK, ASSIGNOR TO GERMAN-AMERICAN
BUTTON COMPANY, OF ROCHESTER, NEW YORK, A CORPORATION OF NEW YORK.

DESIGN FOR A BUTTON.

49,867.

Specification for Design.

Patented Nov. 7, 1916.

Application filed August 30, 1916. Serial No. 117,814. Term of patent 3½ years.

To all whom it may concern:

Be it known that I, RUDOLPH SIEBERT, a citizen of the United States, and a resident of the city of Rochester, county of Monroe, and State of New York, have invented a new, original, and ornamental Design for Buttons, of which the following is a specification.

My design is represented in the accompanying drawing, in which:

Figure 1 is a plan view of a button showing my new design. Fig. 2 is a side view.

The button is in general octagonal in shape, the sides of the four opposite corners, however, are beveled and lie in arcs of circles. The central portion is square and smooth on top, and the portions upon the

outer sides of the central square portion are provided with corrugations and lie in a lower plane than the central portion as shown. The bottom has a central cylindrical projection as shown.

I claim:

The ornamental design for a button substantially as shown and described.

In witness whereof I have hereunto set my hand at Rochester, in the county of Monroe and State of New York, this 25th day of August 1916.

RUDOLPH SIEBERT.

In presence of—

W. D. HULBURT,
EARL A. WELLER.
